[57]

ABSTRACT

A pressure sealing apparatus comprising a seal drum or a seal block having a hole for the passage of cloth, installed on the opening for guiding cloth in and out of a pressure chamber; rolls which are pressed through intermediate rolls on the seal drum or the seal block and are rotated in contact with each other for putting cloth in and out; and a sealing end plate which is engaged with the seal drum or the seal block to be able to move in an axial direction and which is pressed on each end face of the said drum or block and the above-said rolls; and which is characterized in that the before-mentioned sealing end plate is made as a metallic case, having a flexible sealing material laid on the side, which is pressed on the end face of each roll, and the flexible sealing material is uniformly pressed on the end face of the roll by a pressure liquid.

PRESSURE SEALING APPARATUS

This is a division of application Ser. No. 8,548, filed Feb. 4, 1970, now U.S. Pat. No. 3,686,900.

The present invention relates to a pressure sealing apparatus and its connected apparatus, which are used in a high-pressure steam for treatment of textile fibre products, such as yarn or cloth, in the atmosphere of a high pressure and high temperature saturated vapor.

The present inventors have formerly developed a pressure sealing apparatus, which comprises that a seal drum, having a hole for passage of cloth, is installed above the opening for guiding cloth in and out of the high pressure steamer, and a pair of rolls for feeding cloth are pressed on and contacted with the seal drum through a pair of intermediate rolls and rotate in contact with each other, and a sealing end plate is engaged with the seal drum to be able to move in the axial direction and is pressed and jointed with the said drum and the end face of each of the above-said rolls. The main object of the present invention is to make it more perfect to seal between the before-mentioned sealing end plate and the seal drum and the end faces of the rolls.

The first object of the present invention is to ensure a perfect sealing of an inner pressure by the means that the sealing end plate is constructed in a form of a hollow case, having a flexible sealing film on the side which is pressed on the end face of the roll, and being made of a metallic plate on the opposite side, and the above-said flexible sealing film is uniformly pressed on the end face of the roll by a liquid, which is compressed into the said case.

According to the present invention, in order to seal between the seal drum or the seal block and the intermediate rolls, a U-shaped groove is made on the seal drum along the line of contact with the rolls to be embedded with sealing pieces, and a liquid is compressed into the U-shaped groove to make the sealing pieces uniformly pressed on the intermediate rolls, and thus it can be expected to seal more perfectly between the former and the latter.

The second object of the present invention relates to a forced lubricating and cooling method, which comprises that in a pressure sealing apparatus of a roll type, a lubricant is poured into the sealed end portion of the sealing roll in a quantity enough to cool, and lest the poured lubricant should be touched with the passing cloth, in the middle part of the sealing roll, a pressure gas is blown against between the end portion of the sealing roll to push the said lubricant toward the outside from the edge of the cloth.

Generally speaking, in a pressure sealing apparatus of a roll type, friction may be generated between the end faces of the sealing roll and the intermediate roll and the sealing end plate or the seal drum, which is fixed on the side of the pressure vessel. The abrasion of the friction part, the damage from the frictional heat to the sealing agent and the loss of power in driving against this frictional resistance, these impede a practical use of the pressure sealing apparatus. Especially, when the sealing roll is a rubber roll, a frictional heat may be accumulated to shorten the life of the roll.

Therefore, it may be considered to supply a lubricant and a coolant between the sealing rolls and the sealing end plate in the pressure sealing apparatus. But as the circumferential surface of the said sealing roll is contacted with the passing cloth, the above-said lubricant

or coolant adheres to the cloth, when the lubricant and the coolant are simply supplied between the sealing rolls. The said method may often damage the object, such as bleaching, dyeing, etc. in the process of cloth treatment and cannot be put in a practical use.

So, in case of lubrication and cooling of the above-said sealing roll, it is necessary not to damage the object of cloth treatment, namely, not to make a lubricant or a coolant adhere to the cloth.

10 In compliance with this demand, the present invention has accomplished the desired purpose by that a liquid lubricant is poured into the sealed end portion of the sealing roll in a quantity enough to cool and a pressure gas is blown against between the end portion of the sealing roll and thus, the liquid lubricant, poured into the end face of the sealing roll, can be prevented from soaking out in the middle part of the sealing roll, namely in the direction of the cloth.

Further, the present invention relates to a forced lubricating and cooling apparatus for a pressure sealing apparatus, characterized by that in a pressure sealing apparatus of a roll type, the part of the sealing end plate, contacted with the end face of the sealing roll, is grooved in a U-shape for a liquid lubricant, and also a mechanism is provided to pour a liquid lubricant compulsorily into the groove for a liquid lubricant.

Generally speaking, in a pressure sealing apparatus of a roll type, friction may be generated between the end face of the sealing roll or the intermediate roll and the sealing end plate or the seal drum or the seal block, which is fixed on the side of the pressure vessel. The abrasion of the friction part, the damage done by the frictional heat to the sealing agent, and the loss of power in driving against this frictional resistance, these impede a practical use of the pressure sealing apparatus. Especially, when the sealing roll is a rubber roll, a frictional heat may be accumulated to shorten the life of the roll.

40 In compliance with this object, the present invention makes lubrication and cooling more effective between the end face of the sealing roll and the sealing end plate.

According to the present invention, in such a pressure sealing apparatus, packings are laid in order to ensure a more perfect sealing between the sliding parts, namely, between the circumferential surface of the intermediate roll and the upper surface of the seal block and between the inner surface of the sealing end plate and the end face of the intermediate roll and the sealing roll, and besides, the desired object can be achieved more effectively, if an intermediate sheet, composed of teflon and other textiles or sheets, is inserted with a view to make the sealed sliding part to be slidable and lubricative.

55 The third object of the present invention relates to a wiping device, which intends to prevent the surface of the sealing roll from contamination and also to obtain a cooling effect on the surface of the sealing roll in a high pressure steamer.

60 In order to treat cloth chemically (scouring, bleaching, dyeing) under a high pressure and at a high temperature in a pressure chamber, the cloth is airtightly guided in and out of the pressure chamber. The present invention relates also to a jet washing device, which is employed in the above-mentioned guiding apparatus and washes cloth with ejected warm water in order to prevent the cloth from contamination with dyes or

wastes, when the cloth is guided in and out of the pressure chamber in a process to be treated under a high pressure and at a high temperature in the pressure chamber.

Such a device of the present invention will be explained as follows. Two sealing rolls are made up of rotating soft rolls. Intermediate rolls, composed of hard rolls, such as metallic rolls, are pressed by the sealing rolls from above and by sealing pieces from below. The sealing pieces are attached to the portion, through which cloth is guided in and out of the pressure vessel. An end plate is attached to the sealing pieces to be able to slide, and to seal the end face of each of the rolls. And thus, the apparatus to guide cloth in and out, consists of the sealing rolls, the intermediate rolls, the sealing pieces and the end plate. The device is to eject such a washing liquor as a warm water toward the pressing line of the intermediate rolls and the sealing pieces in the above-said apparatus, and to wash away the piled dirt along the down slopes, which are made on the sealing pieces on both sides of the upper part of the through hole for guiding cloth in and out.

An outward ejecting device to make a washing layer with warm water and others may be employed together.

The present invention provides also a device which comprises that in order to treat cloth chemically (scouring, bleaching, dyeing) under a high pressure and at a high temperature in a pressure chamber, the cloth is airtightly guided in and out of the pressure chamber, and revolving brush rolls are installed in a water vat outside the above guiding apparatus, and press rolls are also installed above the surface of the water of the vat, in order to prevent the inner surface of the cloth from contamination with dyes or wastes when the cloth is guided in and out in the cloth treatment process.

Such a device will be explained as follows. The cloth guiding apparatus is composed of rotating soft rolls and rotating hard rolls, pressed directly by the same, and a metal fitting to hold the sealing pieces, and also an end plate to seal the end face of each roll. The metal fitting is pressed through the sealing piece on the hard roll in the upper and is connected through a packing with the pressure chamber in the lower. The apparatus is provided with a water vat on the atmospheric pressure side of each roll. A part of the soft roll and the whole body of the hard roll are sunk into water. Revolving brush rolls are installed in water in contact with the soft rolls and the hard rolls. Moreover, the soft roll is provided with a press roll to be pressed above the surface of the water. The surface of each roll is in water washed by the revolving brush roll and water is taken away from it by the press roll.

The fourth object of the present invention relates to an improvement of a sealing device in the apparatus, which comprises that in order to treat cloth chemically (scouring, bleaching, dyeing) under a high pressure and at a high temperature in a pressure chamber, the cloth is airtightly guided in and out of the pressure chamber.

A seal block, having a flat upper surface and a T-shaped section, is employed instead of the before-mentioned seal drum. The rotating shafts of both the soft rolls (the sealing rolls) and the rotating shafts of the hard rolls are aligned in the vertical plane, laid upward from the upper surface of the seal block. Thus, the sealing between the intermediate rolls and the seal

block and the durability of each roll (the sealing rolls and the intermediate rolls) are considerably improved.

The present invention relates to a device which comprises that sealing rolls, consisting of a different kind of materials, and to put it concretely, a combination of soft rolls, such as rubber coated rolls, and hard rolls, such as metallic rolls are used in a sealing apparatus, and the difference of thermal expansion in the axial direction of both the sealing rolls is absorbed as quickly as possible.

Further, the present invention relates to a pressure sealing apparatus of a high pressure steamer, in which an auxiliary roll is used together to receive the sealing roll in order to reduce the driving power for the sealing roll.

The present invention relates to a sealing apparatus of a roll type, which comprises that a high pressure steamer is used to steam cloth under a high pressure and at a high temperature and a pressure sealing apparatus is installed on the opening for guiding cloth in and out of the high pressure steamer, and the sealing apparatus is attached directly to the cloth guiding outlet and is composed of the first stage of the sealing apparatus, contained in the intermediate pressure vessel, and the second stage of the sealing apparatus, attached to the opening for guiding cloth in and out of the intermediate pressure vessel.

Formerly, it is common to use a one-stage sealing apparatus of a roll type in this kind of the high pressure steamer. The cloth is nipped and guided in and out of the high pressure steamer. As the high temperature and the high pressure inside the steamer are shut off from the outside, the stress of nipping on the sealing roll is quite large, and moreover, as being exposed to the high temperature and the high pressure, the said sealing roll is remarkably short in its useful life.

The present invention is to eliminate such deficiencies as far as possible and to give a more perfect sealing effect, and besides, to prevent such a peril as the case of a roll damage, because the first stage of the sealing apparatus is placed in a casing, namely, in the intermediate pressure vessel.

The present invention relates to a pressure sealing apparatus, which comprises that a pressure sealing body, having a U-shaped section and a passage, is installed on the inlet or the outlet of the pressure chamber, and a pair of the sealing rolls rotate in contact with each other, and a sealing end plate is pressed on the rolls and the end face of the sealing body, and intermediate rolls are, if necessary, installed, leaving a space between them, and thus, the pressure sealing apparatus is composed of the pressure sealing body, the sealing rolls, the sealing end plate and the intermediate rolls; and the pressure sealing body is provided with U-shaped packings, embedded along the line of contact with the interior rolls, and also, with a mechanism to give the action of a pressure liquid upon the packing, and the packing is pressed by means of the pressure liquid on the intermediate surfaces of the sealing rolls or the intermediate rolls, arranged inside the pressure sealing body.

According to the present invention, the intermediate rolls or the sealing rolls are arranged inside the U-shaped sealing body, and as being pressed with the U-shaped packing along the two contact lines, these rolls are two-fold supported and sealed. The sealing between the rolls and the sealing body become more tight and

the intermediate rolls (or the sealing rolls) can be more easily supported. A bending of the intermediate roll inside the sealing body can be prevented by the sealing body, and also, the driving power can be reduced.

As the above-said pressure sealing packing being arranged two-fold, a space is formed between them and a cooling water or a liquid lubricant can be enclosed in it so as to be used, as a distinguishing feature, for cooling of the intermediate rolls or the sealing rolls and for reduction of frictional resistance and decrease of abrasion.

The present invention relates to a pressure sealing apparatus, which comprises that U-shaped packings are embedded in the sealing end plate so endlessly as to encircle the space, surrounded by the rolls and the sealing body; and the packings are pressed simultaneously by the pressure liquid on each end face of the rolls and the sealing body.

The present invention is characterized in that when the sealing roll, the intermediate roll or the sealing body is respectively different in length owing to thermal expansion, for example in case of such a combination that the sealing roll is a rubber roll and the intermediate roll is an iron roll and the sealing body is made of cast steel, even though a minute difference will be in the respective lengths, for example at 150° C, owing to the difference in the thermal expansion coefficient of each material, an uniform pressing can be ensured to obtain the sealing object without difficulty, by means of the U-shaped packings and the pressure liquid mechanism, which is to press the packings on the circumferential surface of the roll.

As it is not necessary to remove the position of the sealing end plate itself, there is such an advantage that the whole structure of the pressure sealing apparatus becomes simple, and the pressing device of the sealing end plate is unnecessary.

The present invention relates to a pressure sealing apparatus, which comprises that in a pressure sealing apparatus for a high pressure steamer, etc., sealing rolls are contained in a single case, and the case is attached to the opening for guiding cloth in and out.

According to the present invention, a pair of intermediate rolls are arranged in contact with the inner surface of a horizontal and cylindrical case, which has a hole for passage of cloth and both end faces. Rolls for putting cloth in and out, rotate in contact with each other and are installed on the intermediate rolls. Thus, the pressure sealing apparatus is constructed in such a manner that the seal drum and the sealing end plate, used in the before-mentioned sealing apparatus, can be omitted, and the said case is attached on the opening for cloth of the high pressure steamer to obtain the desired object.

The present invention will be explained in details referring to the attached drawings. It is to make it easy to understand the present invention, but not to limit the scope of the present invention.

FIG. 1 shows a front view of the first example of embodiment according to the present invention, and

FIG. 2, a vertically sectioned side view of FIG. 1.

FIG. 3 shows a side view of the second example of the pressure sealing apparatus according to the present invention;

FIG. 4, a partly sectioned front view of the same; and

FIG. 5, a plan to explain the principle in FIG. 3 and FIG. 4.

FIG. 6 shows a general side view of the third example of the pressure sealing apparatus according to the present invention;

FIG. 7, a plan of a sealing end plate, shown from its inside, of FIG. 6;

FIG. 8 illustrates a feeding mechanism of liquid lubricants for the sealing end plate of FIG. 6; and

FIG. 9 is a detailed part view to show an example of a groove for liquid lubricants in the sealing end plate of FIG. 6.

FIG. 10 shows a general side view of the fourth example of the pressure sealing apparatus according to the present invention;

FIG. 11 is a side view of the main part of a seal drum of FIG. 10; and

FIG. 12 illustrates a lubricating and cooling mechanism in the seal drum of FIG. 10 and FIG. 11.

FIG. 13 shows a vertically sectioned front view of the fifth example of the apparatus according to the present invention;

FIG. 14, a side view of a part of FIG. 13;

FIG. 15, a detection circuit in the apparatus of FIG. 13;

FIG. 16, a front view of the apparatus of FIG. 13; and

FIG. 17, a side view of FIG. 13.

FIG. 18 shows a vertically sectioned front view of the sixth example of the apparatus according to the present invention.

FIG. 19 shows a vertically sectioned front view of the seventh example of the apparatus according to the present invention;

FIG. 20, a modified example of FIG. 19; and

FIG. 21, a plan of a groove shape in the sealing plate of FIG. 19.

FIG. 22 shows a vertically sectioned front view of the eighth example of the apparatus according to the present invention.

FIG. 23 shows a vertically sectioned front view of the ninth example of the apparatus according to the present invention.

FIG. 24 shows a vertically sectioned front view of the tenth example of the apparatus according to the present invention.

FIG. 25 shows a vertically sectioned front view of the eleventh example of the apparatus according to the present invention.

FIG. 26 and FIG. 27 show respectively a sectioned general front view and a partly sectioned side view of the twelfth example of the sealing apparatus according to the present invention;

FIG. 28, a partly sectioned side view of a soft roll, shown in FIG. 26 and FIG. 27; and

FIG. 29, a side view to indicate the relation between the above-said hard and soft rolls and the sealing end plate

FIG. 30 and FIG. 31 show respectively a side view and a vertically sectioned front view of the thirteenth example of the sealing apparatus according to the present invention.

FIG. 32 shows a vertically sectioned front view of the fourteenth example of the apparatus according to the present invention.

FIG. 33 shows a side view of the arrangement in the fifteenth example of the pressure sealing apparatus according to the present invention;

FIG. 34, a front view of the sealing end plate in the same;

FIG. 35, a section view of FIG. 34; and
FIG. 36, a side view of the arrangement in a modified example of FIG. 33.

FIG. 37 and FIG. 38 show respectively a vertically sectioned front view and a vertically side view of the 16th example of the sealing apparatus according to the present invention.

EXAMPLE 1: (FIG.1 and FIG.2)

(1)(1') show soft rolls for sealing pressure, which are sealing rolls, serving also as nipper rolls for putting cloth in and out. (2)(2') show hard rolls for sealing pressure, which are installed between the rolls (1)(1') and the after-mentioned seal drum (3), and are equivalent to intermediate rolls. (3) shows the seal drum, having a hole (3') for passage of cloth. It has a square body with the upper face, formed into a circular convexly curved surface. The core portion (3'') is projecting from its end face. The seal drum (3) is attached through a flexible film on the outside of the cloth inlet or outlet of the high pressure steamer.

The core portion (3'') of the seal drum (3) is removably engaged with the end portion of the side of the space, formed by the above-said rolls (1)(1')(2)(2') and the drum (3). The end portion is tightly covered with a sealing end plate (4), which is pressed by means of a suitable pressure device to touch with each end face of the rolls (1)(1')(2)(2') and the drum (3).

The sealing end plate (4) is consisting of a metallic case (4''), in which soft sealing materials, such as rubber films, for example, coated with teflon, are put on the side, pressed to the end face of the roll. The metallic case (4'') has a port-hole (5) in its hollow portion in order to pour a pressure liquid, for example, water.

The soft sealing material (4') is laid, as shown with a hatching in FIG. 1, on the line of contact with the rolls (1)(1')(2)(2') and the drum (3), namely, along the fringe of the sealing end plate (4).

As above-mentioned, when water, etc., is poured into the hollow portion of the sealing end plate (4) at such a pressure as being higher than the inside pressure of the high pressure steamer, the soft sealing materials (4'), receiving an even inside pressure in all directions, expand to be pressed by an even pressure on the end face of each roll for sealing, and thus, the inner pressure of the high pressure steamer can be completely sealed.

When the intermediate rolls (2)(2') are indispensable, the seal drum (4) is provided with a U-shaped groove (8) at the line of contact of the drum and the rolls. Soft sealing pieces (6)(6') are, in an inverted U-shape, embedded in the groove, and port-holes (7)(7') are made to pass through from the outside of the drum (4) to the bottom of the U-shaped groove (8).

When a pressure liquid, for example, water is poured through the port-holes (7)(7'), the sealing pieces (6)(6') are, similarly as the before-mentioned, pressed by an even pressure on the end face of each roll, to obtain a complete sealing.

In the above instance, it is explained that a pair of intermediate rolls are to be used, but it is not limited to it. There is no limitation in its numbers. The rolls (1)(1') for putting cloth in and out, may be directly pressed on the seal drum (3), as the intermediate rolls being omitted. The present invention can be similarly applied in these cases.

EXAMPLE 2: (FIG.3 to FIG.5)

(11)(11') show sealing rolls, which rotate in contact with each other and serve also as cloth feeding rolls. (12)(12') show intermediate rolls, which are arranged with a space for passage of cloth, and laid between and touched with the rolls (11)(11') and the after-mentioned seal drum (13).

The intermediate rolls may be omitted. The seal drum (13) is attached through a flexible film on the opening for putting cloth in and out of the pressure chamber. A passing way (14) of cloth is made through the drum, and self-lubricating packings (15) are embedded in the drum along the line of contact with the intermediate rolls (12)(12'). (16) shows a sealing end plate, which is removably engaged with a cylindrical axial portin (13') of the seal drum (13), and is pressed by a suitable pressing device on the end faces of the rolls (11)(11')(12)(12') and the seal drum (13).

(17) shows a pipe for pouring of a liquid lubricant, which is installed by a metal fitting (18) on the sealing end plate (16), so as to pour a liquid lubricant from above between the sealing rolls (11)(11') and the sealing end plate (13).

The liquid lubricant is used not only for lubrication between the sealing rolls and the sealing end plate, but also, for cooling of the sealing rolls, which get warm by friction with the sealing end plate. Therefore, the said liquid lubricant must be used in a sufficient quantity for the cooling.

Water or an emulsified oily agent or a non-ionic surface active liquid agent may be used as a liquid lubricant.

(19) show a pipe for a compressed air, and its spouting mouth is set between the sealing rolls (11) and (11') so as to face a suitable place between the end face of the sealing roll and the edge of the cloth (20). At the same time that the cloth is guided in or out between the sealing rolls (11)(11'), a lubricant is supplied between the end face of the sealing roll and the sealing end plate (16) and a compressed air is blown, as the before-mentioned, against the space between the end portions of the sealing rolls. Thus, as shown in FIG. 5, the lubricant is suppressed in a wedge shape between *a* on the end portion of the sealing roll and cannot soak out so far as the middle portion *b* of the cloth.

The interval *c* between the intervals *a* and *b*, corresponds to the before-mentioned space, against which the compressed air is blown.

EXAMPLE 3: (FIG.6 to FIG.9)

(21)(21') show sealing rolls, which rotate in contact with each other and serve also as cloth feeding rolls. (22)(22') show intermediate rolls, which are arranged with a space for passage of cloth, and laid between and touched with the rolls (21)(21') and the after-mentioned seal drum (23).

The intermediate rolls may be omitted. The seal drum (23) is attached through a flexible film on the opening for putting cloth in and out of the pressure chamber. A passing way (24) of cloth is made through the drum, and self-lubricating packings (25) are embedded in the drum along the line of contact with the intermediate rolls (22)(22'). (26) shows a sealing end plate, which is removably engaged with a cylindrical axial portion (23') of the seal drum (23), and is pressed

by a suitable pressing device on the end faces of the rolls (21)(21')(22)(22') and the seal drum (23).

The sealing end plate (26) consists of an inside teflon plate (a) and an outside iron plate (b), and grooves (27) for a liquid lubricant are cut in a concave shape, as shown in FIG. 7 and FIG. 8, along the portion of contact with the rolls (21)(21')(22)(22') on the inner side of the plate, and port-holes (28)(28') are made on the outer side of the sealing end plate (26) to be connected with the upper and lower ends of the groove (27). A liquid lubricant is poured by force into the port-hole (28) by means of a pump (30) from a tank (29) for a liquid lubricant, and passes through the groove (27) to be exhausted from the port-hole (28'). In this case, the liquid lubricant soaks out between the end face of the sealing roll and the sealing end plate from the groove (27) by the pressure of the forced pouring-in.

Thus, it can be simultaneously done to lubricate between the end face of the sealing roll and the sealing end plate and to cool the frictional face of the same, by means of the liquid lubricant, forcibly poured into the groove for a liquid lubricant on the sealing end plate.

Water or an emulsified oily agent or a non-ionic surface-active liquid agent may be used as a liquid lubricant.

EXAMPLE 4: (FIG.10 to FIG. 12)

(31)(31') show sealing rolls, which rotate in contact with each other and serve also as cloth feeding rolls. (32)(32') show intermediate rolls, which are arranged with a space for passage of cloth, and laid between and touched with the rolls (31)(31') and the after-mentioned seal drum (33). The intermediate rolls may be omitted. The seal drum (33) is attached through a flexible film on the opening for putting cloth in and out of the pressure chamber. A passing way (34) of cloth is made through the drum, and self-lubricating packings (35) are embedded in the drum along the line of contact with the intermediate rolls (32)(32'). (36) shows a sealing end plate, which is removably engaged with a cylindrical axial portion (33') of the seal drum (33), and is pressed by a suitable pressing device on the end faces of the rolls (31)(31')(32)(32') and the seal drum (33).

A groove (37) for a liquid lubricant is cut as long as possible, as shown in FIG. 12, on the surface of the above-said packing (35) in the extent A of contact with the sealing rolls (31)(31') or the intermediate rolls (32)(32'). Port-holes (38)(38') are made to pass from both sides of the packing (35) to the bottom of both ends of the groove (37).

In application of the present invention, a liquid lubricant is poured by force from a tank for a liquid lubricant, through a pump to the port-hole (38), and passes in the groove (37) to lubricate and cool the sealing roll or the intermediate roll, and then, is exhausted from the port-hole (38').

Water or an emulsified oily agent or a non-ionic surface active liquid agent may be used as a liquid lubricant.

EXAMPLE 5: (FIG. 13 to FIG. 17)

An example of embodiment, shown in the drawings, will be explained as follows. (41)(41') show sealing rolls, composed of soft rolls; (42)(42'), intermediate rolls, composed of hard rolls; (43), a sealing end plate; (44), cloth, treated by steaming with a high tempera-

ture and high pressure saturated vapour in the drum (50) of a high pressure steamer; and (45), a seal block, which is attached to the drum (50) by means of a combination of a flexible film (51) and fitting flanges (52)(53).

The seal block (45) is, as shown in FIG. 14, supported on a bolt (56) and set in position. The bolt is screwed into a bracket (54), installed on the frame (55) of the sealing apparatus.

(46)(46') show U-shaped packings, which are embedded in the upper surface of the seal block (45) along the line of sealing. (47)(47') show intermediate sheets, such as teflon textiles or sheets, which are laid over the upper surface and the outward surface of the seal block (45), and are held by the bolts (48) – (48''). A pressure liquid is poured by force inside the U-shaped packings (46)(46') through the port-holes (49)(49'), which are made through the seal block (45). The said packings are to be pressed through shock-absorbing sheets (47)(47') on the intermediate rolls (42)(42').

As shown in FIG. 15, the inner pressure of the drum (50) is detected by a transducer (57) for detection of the drum pressure and signalling of pressure control. At

the same time, the pressure of air from the compressor (58) is changed to the required air pressure by means of an automatic pressure regulating valve (59) and is given to the connected port-holes (49)(49'). Thus, the U-shaped packings (46)(46') are to be expanded toward the circumference of the intermediate rolls (42)(42').

The intermediate sheets (47)(47'), such as, for example, a woven cloth of polyester, a woven cloth of ethylene tetrafluoride fibre, a teflon sheet, etc., having abrasion resisting and self-lubricating properties, are interposed between the packings and the circumference of the intermediate rolls (42)(42').

The intermediate sheets (47)(47') are pushed up by the U-shaped packings (46)(46') to be pressed on the circumference of the intermediate rolls (42)(42'). And thus, the inner pressure of the drum can be sealed.

The similar mechanism can be applied between the sealing end plate (43) and the end faces of the sealing rolls (41)(41') and the intermediate rolls (42)(42'). In this case, as shown in FIG. 15 and FIG. 16, U-shaped packings (46'') are embedded in the inner face of the end plate (43) along the sealing line, and intermediate sheets are provided to cover the inner face of the sealing end plate (43). The U-shaped packings (46'') are to be pressed by a pressure liquid through shock-absorbing sheets (47'') on the end faces of the rolls (41)(41') and (42)(42').

EXAMPLE 6: (FIG. 18)

It will be explained referring to the drawing. Cloths (61) are guided out of the inside of the shell (65) into the atmosphere, as being held between the soft rolls (62)(62'), which are pressed together with each other in the pressure sealing apparatus.

(63)(63') and (64) show respectively hard rolls and a pressure seal drum. These make up the pressure sealing apparatus, with the soft rolls (62)(62'). The rolls (63)(63') are separated from each other, but are respectively contacted with the roll (62) or (62') and the seal drum (64).

The rolls (62)(62') and (63)(63') rotate, as shown with an arrow in the drawing, to guide the cloths (61) out. A lubricating piece (71) is attached to the part of

the seal drum (64), which is rubbed with the rolls (63)(63').

The space (72), surrounded by the rolls (62)(62') and (63)(63'), (the openings at both ends of the space, not shown in the drawing, are closed by the sealing end plate), is connected with a slit (73), which links to the shell (65) of the seal drum (64). (74) shows a flexible plate, which is attached to the opening for guiding cloth out (or the opening for guiding cloth in) of the shell (65). The seal drum (64) is laid on the plate.

In the above-said case, starches and dyes, which are stuck on the cloths (61) and not yet adsorbed, and other mixed impurities are transferred on the surface of the soft roll (62) to stain the roll face.

In the present example, such a washing device as shown in the drawing, is arranged as a help to prevent the face of the soft roll (62) from soil and to cool the surface of the soft roll (62).

(66) show a shower pipe for spouting a washing liquor; (67), a brush roll for washing dirts from the face of the soft roll (62); (68), a sponge roll for absorbing a filthy water from the face of the soft roll; (69), a rubber roll for pushing a filthy water out of the sponge roll (68); (70), a water tank for collecting water in one place after washing so as not to scatter excessive sprays around; and (62) (66)(67)(68)(69)(70) are arranged downward from above in the order of (62)(66)(67)(68)(69)(70).

The brush roll (67), the sponge roll (68) and the rubber roll (69) rotate as shown with an arrow, and can achieve the object in preventing the roll face of the soft roll (62) from soil and in cooling the same.

EXAMPLE 7: (FIG.19 to FIG. 21)

In FIG. 19, (81)(81') show soft rolls, which are pressed on each other by suitable bearing, driving and pressing devices, and hold cloth (87) airtightly between the rolls and guide it in and out. And at the same time, the rolls are pressed on and rotate the hard rolls (83)(82'), which are arranged below.

The hard rolls (82)(82') are facing each other, with a space for passage of cloth, and rotate, as being pressed on the packings (84)(84'), which are embedded in the upper part of the sealing plate (83).

The sealing plate (83) has an even upper face and is connected in the lower part with the pressure chamber, and holds the packings (84)(84'), embedded in the upper face.

And also, it has a face, sloping down toward the inner face from the pressing line of the hard roll, on both sides of the upper part of the hole (88) for passage of cloth.

The packings (84)(84') of the sealing plate are suitable abrasion resisting elastic bodies and are pressed on and hold the hard rolls airtightly. (85)(85') show warm water jetting nozzles, which pass through the sealing plate from the outside and open on the inside to the contact line of the roll (82) and the sealing plate (83). (86)(86') show warm water jetting nozzles for the outside portion. Warm water is jetted from either nozzle at suitable intervals at a right angle to the pressing line of the hard roll and the sealing plate.

The positions, the intervals and the numbers of the water feeding device and the nozzle may be suitably determined.

Dyes, wastes, etc., which stick, as dews, to the soft roll and the hard roll, and flow down below and pile in

the neighbourhood of the pressing line of the intermediate roll and the sealing plate, are washed off by the above jet washing device to the bottom of the pressure chamber along the faces on both sides of the hole for passage of cloth in the sealing plate. Thus, each roll can be kept clean, and the abrasion may be reduced on the roll. The cloth can be prevented from soil and guided in and out in a perfect airtightness.

In case of a change in the process, a colour change 10 and others, the cleaning hour may be shortened to improve the efficiency.

FIG. 20 shows a variation of FIG. 19, which is similar to that of FIG. 19, except that the sealing plate is made in a shape of a drum with a convex surface.

In this case, a washing liquor stands on the line of contact of the intermediate roll (82) and the drum-shaped sealing plate (83). In order to flow the washing liquor away into the pressure chamber, instead of the sloping faces (84') of FIG. 19, drain grooves (83'') are provided to pass, as shown in FIG. 20, from the said contact line down to the hole (88) for passage of cloth and horizontal drain grooves (83''') are adopted to connect these grooves (83'').

EXAMPLE 8: (FIG. 22)

In the drawing, (101)(101') show soft rolls, which are beared by a suitable bearing device and are pressed on each other by a suitable pressing device and a driving device. The cloth (111) are held between the rolls and guided in and out. The rolls are pressed on and rotate the hard rolls (102) (102'), which are arranged below.

The hard rolls (102)(102') are facing each other, with a space for passage of cloth, and rotate as being pressed on the sealing pieces (104)(104'), which are embedded in the upper part of the metal fitting (103) for holding the sealing pieces.

The metal fitting (103) for holding the sealing pieces 40 is connected, on the lower part, through the packings, with the pressure chamber, and holds the sealing pieces (104) (104'), embedded in the upper part. The sealing pieces (104) (104') are suitable abrasion resisting elastic bodies, and are pressed on the hard roll to be airtight, through the U-shaped packings (105)(105') by the liquid pressure from the ports (106)(106'), which pass through the metal fitting for holding the sealing pieces.

(107)(107') and (104)(108') show revolving brush 50 rolls, which are installed in a water vat respectively in contact with the soft rolls (101)(101') and the hard rolls (102)(102'), and are rotated by a suitable bearing device and a driving device.

(109)(109') show press rolls, which have suitable 55 bearing, driving and pressing devices, and are pressed on the soft roll above the surface of water to take away water from the surface of the roll,

(110) shows a water vat, which is provided with a water supply hole and a drain hole. A suitable type may 60 be selected from such as a water-supplying means from above, a bottom drainage, an under water-supplying means, an overflow drainage, etc.

By the above-said washing device the face of each roll can be kept clean and the abrasion may be reduced on the roll. The cloth can be prevented from soil and guided in and out in a perfect air-tightness. In case of 65 a change in the process, a colour change and others,

the cleaning hour may be shortened to improve the efficiency.

EXAMPLE 9: (FIG. 23)

(121)(121') show soft rolls, which are beared by a suitable bearing device and are pressed on each other by a suitable pressing device and a driving device. The cloth (132) is held between the rolls and guided in and out. The rolls are, besides, pressed on and rotate the hard rolls, which are arranged below.

The hard rolls (122)(122') are facing each other with a space for passage of cloth and are pressed on the sealing pieces (124)(124'), which are embedded in the upper part of the metal fitting (123) for holding the sealing piece. At the same time, the rolls rotate in contact with the supporting pieces (125)(125'), which are embedded in the extended portion of the metal fitting for holding the sealing piece. The supporting piece is composed of an abrasion resisting elastic body and may be selected from those, having least frictional resistance. The metal fitting (123) for holding the sealing piece is connected on its lower part with the pressure chamber through the packings, and is holding the sealing pieces (124)(124') and the supporting contact pieces (125)(125'), embedded in the upper part. The sealing pieces (124)(124') are suitable abrasion resisting elastic bodies and are pressed on the hard rolls to keep airtightness, through the U-shaped packings (126)(126') by the liquid pressure from the ports (127)(127'), which pass through the metal fitting for holding the sealing piece.

(128)(128') show revolving brush rolls, which are installed in a water vessel in contact with the soft rolls (121)(121') and are rotated by a suitable bearing device and a driving device.

(129)(129') show press rolls, which have suitable bearing, driving and pressing devices, and are pressed on the soft rolls above the surface of the water to take away water from the surface of the rolls.

(130) shows a water vessel, which surrounds the outside part of each roll and contains the revolving brush rolls and the extended portion of the metall fitting for holding the sealing piece. It is provided with a water supply port in the inside and an overflow near the water surface.

(131) shows a cover for the water vessel. It is detachably set on the upper part of the water vessel, in order to protect against dust and danger and to keep warm.

By the above washing device, the face of each roll can be kept clean and the abrasion may be reduced on the roll. The cloth can be prevented from soil and guided in and out in a good airtightness. In case of a change in the process, a colour change and others, the cleaning hour may be shortened to improve the efficiency.

EXAMPLE 10: (FIG. 24)

(141)(141') show soft rolls (sealing rolls), which are pressed on each other by suitable bearing, driving and pressing devices, and the cloth (147) is held airtightly between the rolls and guided in and out. At the same time, the rolls are pressed on and rotate the hard rolls (intermediate rolls) (142)(142'), arranged below.

The hard rolls (142)(142') are facing each other with a space for passage of cloth and rotate as being pressed on the packings (144)(144'), which are em-

bedded in the upper part of the seal block (143) with a T-shaped section.

The seal block (143) has a hole (148) for passage of cloth penetrated and has an even upper face and is connected, at the lower part, through a flexible plate with the inlet or outlet of the pressure chamber and holds the packings (144)(144'), embedded in the upper face on the right and left sides.

The packings (144)(144') are suitable abrasion resisting elastic bodies, and are pressed on the hard rolls to keep airtightness.

The rotating shafts (145)(145') and (146)(146') of the soft rolls (141)(141') and the hard rolls (142)(142') on both sides are respectively in the planes (P₁)(P₂), which are laid at a right angle on the upper face of the seal block (143). Therefore, the contact line (L₁)(L₂) of the soft rolls and the hard rolls, and the contact line of the hard rolls and the seal block, and also, the packings (144)(144') are respectively in the above-said planes (P₁)(P₂).

Thus, the sealing rolls (141)(141') and the intermediate rolls (142)(142') can be arranged with an excellent sealing function on the seal block (143) without using other supporting means, for example, an auxiliary roll for receiving pressure, and the durability can be remarkably increased because each roll does not receive a overbalancing power.

(149) show a sealing end plate, which is pressed uniformly on each end face of the rolls (141)(141'), (142)(142') on both sides, and is slidably mounted on the head of the T-shaped block (143).

EXAMPLE 11: (FIG. 25)

(151)(151') show sealing rolls, such as, for example, rubber rolls, serving as nippers, which are rotated in the direction of an arrow, in contact with each other. Rolls (152)(152') of, for example, metal, are mounted on the sealing rolls and moved in compliance with the drive of the rolls (151)(151').

(153) shows a seal body, which has a nearly T-shaped section and a hole (154) for passage of cloth in the middle and is attached through a flexible plate (156) on the cloth inlet of the high pressure drum (155).

(157)(157') show intermediate rolls, installed between the rolls (151)(151') and sealing pieces (158), which are embedded in both sides of the hole (154) of the seal body (153). The intermediate rolls are moved in compliance with the rolls (151)(151') and are slid on the sealing pieces (158). (159) shows a sealing end plate, which is, at the lower part, slidably engaged with the head of the T-shaped portion of the seal body (153) and is pressed together on the end faces of the rolls (151)(151'), (152)(152') and (157)(157'). (160) shows a doctor, which is installed on the rolls (152)(152') in contact with them.

Thus, a dye vat or a vat of other chemicals (161) is composed in one body, surrounded with the above rolls (151)(151'), the rolls (152)(152') and the sealing end plate (159)(159').

According the present invention, the cloth (162) enters, first, into the chemical vat (161) and is saturated with chemicals. Without delay it is nipped by the rolls (151)(151') to be squeezed at a suitable pick-up, and is, as it is, guided in the high pressure drum (155). The cloth, soaked with dyes or other chemicals, is, without exposing to air, guided in the high pressure vessel, so

that it can be gotten rid of the troubles, generated by the contact with air.

When the nip-pressure in the nipper rolls (151) (151'), serving as the sealing rolls, is set corresponding to the pick-up of the cloth, the desired pick-up can be simultaneously obtained.

EXAMPLE 12: (FIG. 26 to FIG. 29)

In FIG. 26 and FIG. 27, the sealing rolls are composed of a pair of soft rolls (171) (171'), rotating in contact with each other. The seal drum (175), having a hole (174) for passage of cloth, is attached through a flexible film (173) to the opening (172) for guiding cloth in and out of the high pressure steamer. A pair of hard rolls (176) (176') are installed between the above-said sealing rolls and the seal drum, and have a space for passage of cloth between each other. The sealing end plate (177) is mounted on the seal drum to be slideable in an axial direction and pressed on the end faces of both the rolls. The pressure sealing apparatus has been, thus, developed to be composed of the sealing rolls, the seal drum, the hard rolls, and the sealing end plates. But, a metallic roll (a), laid with a rubber coating (b), is used as the above-said soft roll (171) (171'), while, a metallic roll is used as the hard roll (176) (176'). When the rolls (171) (171') and (176) (176') are respectively composed of a different kind of materials to be used in combination as the sealing rolls of the high pressure steamer, the metallic rolls (176) (176') are quickly gotten warm by the high temperature inside the high pressure steamer, while the rubber-coated rolls (171) (171') have the metallic cores (a) of the roll heated and warmed through the rubber coatings (b). There is a great difference in the speed of thermal expansion between both the rolls (171) (171') and (176) (176').

Therefore, as shown also in FIG. 29, at the starting time of operation in the high pressure steamer (178), the metallic rolls (176) (176') are quickly expanded by heat, while the rubber coated rolls (171) (171') are retarded to be expanded by heat. During the time until the rolls (171) (171') get at a thermal balance, the rolls (176) (176') are pressed together on the sealing end plate (177), while there is a gap (179) between the rolls (171) (171') and the sealing end plate (177). The high pressure treatment cannot be performed owing to a steam leakage. Therefore, the aimed sealing object cannot be achieved and the contact portion of the metallic rolls (176) (176') and the sealing end plate (177) are abraded vehemently.

Besides, according to the results of the experiments, it takes from about 2 1/2 to 3 hours until the rolls (171) (171') get at a thermal balance and show a similar thermal expansion to the rolls (176) (176'), even when the rubber coating (b) of the rolls (171) (171') is about 10 - 20mm in thickness. It causes also a great disadvantage in the operation efficiency.

In the present example, in order to get rid of such a deficiency, a heating liquid, such as steam or other is positively supplied inside the metallic core of the rubber coated soft roll so as to make considerably short the time of warm-up in the rubber coated soft roll.

In the pressure sealing apparatus according to the present invention, the rubber coated soft roll is heated with steam positively from inside, and thus, the soft roll is made almost similar to the hard roll, such as a metallic roll, in the speed of thermal expansion. It becomes

about 1 1/2 hour to complete the sealing of the above roll and the sealing end plate. It is 1 to 1 1/2 hour shorter than that in case of steam being not passed through the inside of the soft roll.

- 5 If it is computed in the length of the treated cloth, it corresponds to 2,400 - 3,600m. And, moreover, it is accumulated every day. When the present invention is applied, the efficiency will be significantly improved in the operation of the high pressure steamer.
- 10 In the application of the present invention, a heating liquid, such as steam or other, is passed through the inner side of the rubber coated roll, as well as a liquid coolant may be passed through the inner side of the metallic roll. It makes it further shorter and effective to complete the sealing.

The general view of the pressure sealing apparatus is as shown in FIG. 26 and FIG. 27. And the rubber coated roll (171) has been improved by the present invention. As shown in FIG. 28, the rubber coated roll (171) has such a soft coating (181) as rubber or others on the surface of the iron core (180) of the roll. (182) shows a port-hole, which passes to the inside (185) of the iron core (180) of the roll and the other end of the port-hole is connected through a rotary joint (183) to the steam port (184). The other end of the inside (185) of the iron core of the roll comes to the drain outlet (186).

According to the present invention, a heating liquid is passed through inside the roll, having a soft coated metal core, and the roll is positively heated from the inside of the metal core. Therefore, though the sealing apparatus is composed of rolls of a different kind of materials, it can be considerably shortened in time to complete the sealing between each roll and the sealing end plate. It brings about a quite effective result.

EXAMPLE 13: (FIG. 30 and FIG. 31)

It will be explained referring to the drawings, (201) shows comparatively soft sealing rolls, which rotate, as being pressed on each other. (202) shows a seal drum, which has a slit (203) for passage of cloth, and is mounted on a flexible film (206), attached to the inlet or outlet (207) of the high pressure steamer. (207) shows a comparatively hard intermediate roll, which is arranged between and contacted with the sealing roll (201) and the seal drum (202). (208) shows a sealing end plate, which is engaged with the seal drum (202) and is pressed on the end faces of the rolls (201) (207). A self-lubricating material is embedded in the place, where the seal drum (202) contacts with the intermediate roll (207).

According to the present invention, an auxiliary roll (209) are installed to receive the middle portion of the intermediate roll in the above-mentioned sealing apparatus.

The auxiliary roll (209) is sustained on a bracket (211), attached on the base (210). The bracket (211), accordingly the auxiliary roll (209) is regulated to be moved by an adjusting screw (212), set on the base (210). Thus, the supporting level of the intermediate roll (207) can be finely adjusted.

In such a pressure sealing apparatus as the above-mentioned, the intermediate roll (207) receives always a bending power from the sealing roll (201), and is powerfully pressed on the seal drum (202) so that a large power is needed to drive the intermediate roll (207).

As proposed by the present invention, if the intermediate roll (207) is to be received by the auxiliary roll, the load of the intermediate roll (207) on the seal drum (202) could be reduced and the driving power of the roll (207) might be smaller.

EXAMPLE 14: (FIG. 32)

(221) shows an opening for guiding cloth in and out of the drum of the high pressure steamer and is attached with a sealing body (222), having a hole (222') for passage of cloth.

A pair of sealing rolls (224), serving also as nippers, which rotate as being pressed on each other and are installed on the sealing body (222) through a pair of intermediate rolls (223), pressed to the sealing body (222). The rolls (223)(224) are contained in the intermediate pressure vessel (225), serving also as a cooling water tank, which is composed of an airtight casing, attached to the sealing body (222).

The roll (223) is contacted with the sealing body at the position of the sealing pieces (226)(226'), which are embedded in two places on the sealing body (222). The sealing piece (226) receives directly the pressing power of the roll (224) and is supported through a U-shaped packing by a pressure liquid from the outside.

(227) shows a brush roll, which is arranged in contact with the roll (224). (228) shows a roll which serves to prevent the roll (224) from bending and to take away water from the same.

The second stage of the sealing apparatus on the opening (225') for guiding cloth in and out of the above-said casing (225), is composed of a sealing roll (229) (coated with such an elastic body as rubber and other), serving also as a nipper, which rotates as being pressed on each other and is installed on the sealing piece (230), embedded in the casing (225). (231) shows a roll, which serves to prevent the roll (229) from bending and to take away water from the same, and the rolls (229)(231) are contained in a cooling liquor vat (232).

(233)(234) show sealing end plates, which are respectively attached to the first and second stages of the sealing roll. (233')(234') show packings for the same.

When the inner pressure P_1 of the drum (221) of the high pressure steamer is about $3.2\text{kg}/\text{cm}^2\text{G}$, and the inner pressure P_2 of the intermediate pressure vessel (225) is $1\text{kg}/\text{cm}^2\text{G}$ at most, it will do well if the sealing effect of $2.2\text{kg}/\text{cm}^2\text{G}$ can be obtained in the stage of the sealing apparatus, namely on the roll (224), and that of $1\text{kg}/\text{cm}^2\text{G}$, in the second stage of the sealing apparatus, namely on the roll (229). As compared with the conventional one stage sealing apparatus, it can obtain a perfect sealing effect under a comparatively unsevere condition of the roll pressing. By the way, P shows an atmospheric pressure.

If a cooling water is kept so as to submerge almost the lower half part of the roll (224), as shown in the drawing, in the intermediate pressure vessel (228), it can be simultaneously done to cool the sealing roll (224), composed of such an elastic roll as rubber.

EXAMPLE 15: (FIG. 33 to FIG. 36)

In FIG. 33, (241)(241') show pressure sealing rolls; (242)(242'), intermediate rolls; (243), a pressure sealing body; (244)(244') and (245)(245'), U-shaped packings, which are inserted in the groove, cut along the longitudinal direction on the pressure sealing plate

and are pressed on the circumference of the intermediate rolls (242)(242') by the pressure liquid of the inside of the groove; and (246)(246'), port-holes, which guide the pressure liquid in the above-said groove. The sealing body (243) of the pressure sealing apparatus is attached through a flexible film (248) to a high-pressure chamber (247) at a suitable interval from the circumference of the intermediate rolls (242)(242'), which are installed by a suitable suspending device.

The pressure liquid is poured through the port-holes (246)(246') so as to press the circumference of the intermediate roll with such a power as to be necessary and sufficient for sealing the pressure of the inside of the pressure chamber. The U-shaped packings for sealing pressure are pressed along the inner face of the groove on the circumference of the intermediate sealing roll. The pressure sealing packings are installed at two stages and a liquid, such as a cooling water or other lubricating oil, can be enclosed in the spaces (249)(249') between the packings (244) and (244'), as well as between (245) and (245'). Then, it can be expected to reduce the frictional resistance or to decrease wearing of the intermediate rolls.

FIG. 34 shows a front view of the sealing end plate. The packing (250) is inserted as shown in FIG. 35. The pressure liquid is poured in through the port-holes (251) or (252). Thus, the packing is simultaneously pressed on the end faces of each sealing roll and the sealing plate to complete the sealing.

FIG. 36 shows another example of the present invention. The hard intermediate rolls (242)(242') are arranged at intervals from each other in the concave portion of the pressure sealing body and are supported at two points respectively on the packings (244)(244') or (245)(245'). One soft sealing roll (241) is installed above the intermediate rolls (242)(242') to rotate in contact with them together. The cloth is to pass through between the rolls (241) (242) or between (241)(242') and by way of the space of the rolls (242)(242'), to go in the pressure chamber (247) through the hole for passage of cloth of the sealing body (243).

EXAMPLE 16: (FIG. 37 and FIG. 38)

(261)(262) show respectively a covering body and a vessel body, which are the component parts of the horizontal cylindrical case, divided into halves horizontally. The covering body (261) has a hole (263) for passage of cloth. The vessel body (262) has a base (265), forming a hole (264) for passage of cloth (264). The vessel body (262) is attached at the base (265) through a flexible film to the opening for putting cloth in and out of the high-pressure steamer.

(266)(266') show intermediate hard rolls, which are arranged in contact with the inner face of the vessel body (262), and are separated from each other by the hole (264) for passage of cloth. A self-lubricating sealing material (267), such as teflon, is applied to the face of the vessel body (262), which contacts with the rolls (266)(266'). (267) (267') show soft rolls, which are pressed on the intermediate rolls (266)(266') and rotate in contact with each other to put cloth in and out.

(268) show an end plate of the case, which is composed of the covering body (261) and the vessel body (262). The plate is attached to the case so as to be pressed through the sealing material (269) on the end faces of the rolls (266)(266') and (267)(267'), or is

pressed towards the end face of the roll by a suitable pressing device. (270) shows a passing way of cloth.

According to the present invention, the desired object for pressure sealing can be accomplished by the apparatus of a compact structure.

We claim:

1. A forced lubricating and cooling device for a pressure sealing apparatus comprising a pair of sealing rolls rotating in contact with one another, a sealing end plate pressed in contact with the end faces of said sealing rolls, means for introducing a liquid lubricant in a quantity sufficient for cooling between the end faces of said sealing rolls and the surface of said sealing end plate contacting the end faces, and means for blowing a pressure gas against the end portions of said sealing rolls for pushing the liquid lubricant so that the lubricant does not contact the cloth which passes between said sealing rolls.

2. A forced lubricating and cooling device for a pressure sealing apparatus comprising a pair of sealing rolls rotating in contact with one another, a sealing end plate pressed in contact with the end faces of said sealing rolls, a groove having a concave shape formed in the

surface of said sealing end plate in contact with said sealing rolls, and means for introducing a liquid lubricant by force into said groove.

3. A forced lubricating and cooling device for a pressure sealing apparatus comprising a seal drum forming a pressure chamber and having an opening for guiding cloth in and out of the pressure chamber, a pair of rolls in contact with said sealing drum on the opposite sides of the opening for the cloth, and groove of U-shaped configuration formed in the surface of said seal drum which contact said rolls, and means for introducing a liquid lubricant under force into said groove.

4. A pressure sealing apparatus of a roll type, comprising sealing rolls formed of different kinds of material and including first sealing rolls formed of a soft coated roll and second sealing rolls formed of a metallic surface roll, a sealing plate pressed in contact with the end faces of said sealing rolls, said soft coated rolls having a metal core and said metal core having an axially extending bore therethrough, and means for passing a heated liquid through the bore in said metal core for making the completion time for sealing shorter.
